UNITED STATES PATENT OFFICE.

CHARLES GLOVER, OF NEW BRITAIN, CONNECTICUT.

DESIGN FOR A BICYCLE PEDAL MEMBER.

SPECIFICATION forming part of Design No. 29,828, dated December 20, 1898.

Application filed November 2, 1898. Serial No. 695,328. Term of patent 7 years.

To all whom it may concern:

Be it known that I, CHARLES GLOVER, a citizen of the United States, residing at New Britain, Hartford county, Connecticut, have invented and produced a certain new and original Design for a Bicycle Pedal Member, of which the following is a full, clear, and exact description.

My invention relates to a new and original design for a bicycle pedal member.

The accompanying drawings illustrate, in Figure 1, a plan view, and in Fig. 2 a side elevation, of my new and original design.

This pedal member when viewed in plan, as shown in Fig. 1, suggests in form the letter C. As the letter C which the plan view suggests is not strictly of the conventional outline, the appearance of the pedal member

might be described as follows: There are two substantially-parallel sides A and B, connected at one end, as at C, and the opposite ends of the sides A and B show enlargements D and E.

The said pedal member when viewed in side elevation, as shown in Fig. 2, appears to have one of its edges irregularly formed and turned up toward the point indicated by the letter C.

What I claim is—

The design for a bicycle pedal member substantially as herein shown and described. 30

Signed at New Britain, Connecticut, this 31st day of October, 1898.

CHARLES GLOVER.
